LIGHT WEIGHT T-20 SHOULDER STOCK FOR 3.5 INCH ROCKET LAUNCHER

Herbert Harvey, Redondo Beach, and Stephen A. Stam, Glendale, Calif., assignors, by mesne assignments, to the United States of America as represented by the Secretary of the Army

Application March 7, 1956, Serial No. 570,196

2 Claims. (Cl. 89—1.7)

This invention relates to an interchangeable ground and shoulder mount for rocket launchers.

Launchers used in mounts of this type are usually those of the M20 or M20B1, 3.5 inch class. They may employ a forward bipod section and a rearward section consisting of a combined leg and shoulder stock. In order to use the launcher upon the shoulder, the forward bipod must be folded into stowed position. Hence the launcher carries the added weight of the bipod at all times. With the present invention, the launcher may be quickly dismounted from the tripod and with a minimum of manipulation can be converted into a mobile lightweight launcher to be fired from the shoulder of the gunner.

Hence, an important object of this invention is to provide a ground mount of three sections, quickly dismounted and of lightweight construction throughout.

Another object of the invention is to provide a mounting mechanism that will provide precise yet rapid controlled adjustment in elevation and free traverse in azimuth.

A further object of the invention is to provide a launcher mounting mechanism permitting the launcher to be readily converted from a ground mounted field-piece to a mobile shoulder-supported mount.

A still further object of the invention is to provide a mount to be used with existing tripods for launchers of this type.

Other objects and advantages of the invention will become apparent during the course of the following description:

In the accompanying drawings, forming a part of this specification, and in which like numerals are employed to designate like parts throughout the same:

Figure 1 is a side elevation of a launcher mounted for shoulder firing and illustrates the shoulder stock.

Figure 2 is a sectional view taken along the line 2—2 on Figure 1 looking in the direction of the arrows.

Figure 3 is a partial perspective view of the ends of the shoulder stock showing clamp members attached thereto.

Figure 4 is a perspective view showing a launcher mounted upon the cradle section and also mounted upon a tripod for firing from a prone or sitting position, the shoulder stock section being in stowed position.

Figure 5 is a perspective view of the shoulder stock mounted upon the firing position clips that are mounted in the mounting bands.

Figure 6 is a sectional view taken along lines 6—6 on Figure 5 and looking in the direction of the arrows, showing the mounting band adjusting means.

Figure 7 is a side elevation, partly broken away, illustrating the cradle member and elevational adjustment of the same.

Figure 8 is a fragmentary front view of the cradle and, Figure 9 is a top plan view of the cradle.

In the drawing, wherein for the purpose of illustration is shown a preferred embodiment of the invention, 1 indicates generally a tripod of either the M77 or M1917

2

mount class and consisting of ground engaging legs 2 adjustably mounted to a pintle socket member 3. 4 indicates generally a cradle section, comprising a yoke member 5 pivotally mounted by a nut and a bolt 6 to 5 a pintle frame section 7. Belleville spring washers 8, Figure 8, between the frame 7 and yoke 5 provides friction between the frame and yoke. Elevational control of the yoke 5 is obtained by turning a hand wheel 9 mounted at one end of an elongated shaft 10 journaled 10 in bearings 11 integrally mounted from the lower surface of yoke 5. A worm 12 is fixed on the other end of shaft 10 and meshes with a pair of arcuate internal gear segments 13 fixed to the floor of the frame 7. Additional frictional braking action is afforded the yoke, 15 necessary to overcome the unbalance of the launcher about the pivot 6 when elevating or depressing, by a brake member 14 carried by the forward under surface of the yoke 5 and which bears against the inner sides of the gear segments 13. A pintle 16 is attached to 20 the under face of frame 7 by bolts 15 and is adapted to fit within the pintle socket member 3 of the tripod 1 whereby the frame and parts supported thereby may be trained as a unit in azimuth.

Forward and rearward mounting lugs 17 and 18 are 25 formed integrally on the respective ends of the upper surface of yoke member 5 for mounting forward and rearward launcher tube mounting bands 19 and 20 respectively, by pins 21 and 22. These bands are adapted to receive the launcher tube 23. The bands 19 and 20 30 are similar in construction and consist of a flexible strap adapted to surround the tube of the launcher.

As clearly shown upon Figure 5, each band is formed 35 with an adjustable connection whereby its effective length may be varied to contract the same about the launcher tube. Thus, referring to Figures 5 and 6, one end of each strap is split and the two parts thus formed are rolled or looped as at 23a to rotatably receive the ends of a draw pin 23b. The mid portion of this pin is transversely drilled to rotatably accommodate a screw 24a 40 whose threaded end engages a tapped hole in the other and thickened end 24 of the strap. Thus each band may be contracted about the tube by turning of screw 24a.

From inspection of Figures 2 and 5 it will be noted 45 that each strap has a tapered undercut lug or bracket 25 secured, as by welding, to its lower surface. Each lug forms a portion of a bayonet joint for a purpose subsequently explained. Similar tapered lugs 26 are provided upon the upper and outer side of the bands 19 and 20.

50 Spaced depending apertured ears or lugs 27 are provided on each of the bands 19 and 20 on respective sides of the lug 25 for mounting the bands on the yoke member 5. This mounting is effected by pins 21 and 22 which pass through the respective pairs of depending ears and 55 the upstanding lugs 17 and 18 on yoke member 5, received between them. The lugs 25 and 26 are adapted to receive tapered clips 29 and 30 respectively, fixed to the ends of a shoulder stock 28. The shape and construction of this guard are obvious from inspection of Figures 1, 4 and 5. Figure 4 shows the guard attached to lugs 26 while Figures 1 and 5 show it attached to lugs 25.

To install the mounting bands 19 and 20 upon a launcher tube, bands 19 and 20 are placed about the tube and clamped thereto by turning the screws 24a. The bands are then attached to the cradle section by the pins 21 and 22, and the assembly is mounted to the tripod 1 by insertion of the pintle 16 into the pintle socket 3 of same. The shoulder stock 28 is mounted upon lugs 26 by its clips 29 and 30 whereby it is secured in the position shown upon Figure 4. The launcher is now in position for firing from prone or sitting position.

To prepare the launcher for shoulder firing, the mounting bands 19 and 20 are disengaged by removing pins 21 and 22 and lifting the launcher from the cradle. The shoulder stock is disengaged from its position on lugs 26 and mounted as follows: engage the forward clip 29 of the shoulder stock on the forward lug 25 on band 19, which lug is located between the apertured ears 27 and secure it firmly by striking it with the hand. Then pull the rear clip 30 of the shoulder stock 28 behind the rear lug 25 against the spring force of the stock and allow the clip 30 to slide forward on its lug. Strike the stock firmly with the hand to secure the clip (see Figure 5). The launcher is now ready for use as a shoulder fire piece. It is to be noted that the natural resiliency of the metal of stock 28 retains it against displacement from the lugs 25.

From the foregoing, it can be seen that a launcher mount has been provided that can be quickly converted from a ground mount to a shoulder mount with a minimum amount of manipulation. Greater mobility is also achieved as well as a lighter launcher due to elimination of the tripod when used as a shoulder firing piece. The mounting band may be of welded construction throughout to provide greater strength. The shoulder stock may be of lightweight construction and may be ribbed for rigidity.

It is to be understood that the form of the invention herein shown and described, is to be taken as a preferred example of the same, and that various changes in the shape, size and arrangements of parts may be resorted to without departing from the spirit of my invention, or the scope of the subjoined claims.

What is claimed is:

1. In a mount for a rocket launcher tube, a pair of split rings encircling said tube, in axially spaced relation therealong, each said ring terminating at one of their ends thereof in a pair of spaced loops and at their other ends in a thickened portion, means for tightening said rings about said tube comprising a draw pin rotatably mounted in said loops, a screw transversely piercing said draw

25 pins at a medial point and being disposed between said loops, each said screw to be received in a threaded hole in each said thickened portion, a tapered bracket secured to the underside of each said ring and a shoulder stock 5 having a tapered clip secured to its respective ends adapted to fit a respective bracket on said rings, said brackets and said clips tapering in opposite directions whereby the resiliency of said stock releasably retains said stock on a pair of said brackets.

2. In a mount for a rocket launcher tube, a pair of bands clamped about said tube in axially spaced relation therealong, a tapered mounting bracket secured to each said band, each said lug tapering in an opposite direction with respect to the other, a shoulder stock comprising a 15 length of contoured resilient material and a pair of oppositely tapering clips secured to the respective ends of said stock, each said clip being adapted to receive a respective bracket by opposed sliding movement of the respective ends of said stock parallel with the axis of said tube, said brackets being tapered in the direction of the respective end of said tube whereby the resiliency of said stock releasably retains each said clip in engagement with its respective bracket.
